(57) **CLAIM**

The ornamental design for an article carrier, as shown and described.

DESCRIPTION

FIG. 1 is a top, front, and left side perspective view of an article carrier showing my new design;

FIG. 2 is a top, rear, and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a top, front, and left side perspective view of an article carrier illustrated without broken line portions.

The surface shading illustrated in the drawings highlights the contour of the design; it is not intended to be illustrative of texture, material, or surface ornamentation. The shorter broken lines illustrate portions of the article carrier that form no part of the claimed design. The longer broken lines depict environmental subject matter and form no part of the claimed design. The environmental subject matter is depicted as transparent to illustrate portions of the design otherwise hidden. The broken away and bracketed portions in FIGS. 1–6 indicate that no particular length is claimed for those portions; such lines and any portion between such lines form no part of the claimed design.
